UNITED STATES PATENT OFFICE.

PETER KRAUSHAAR, OF MONTEBELLO, CALIFORNIA.

PHONOGRAPH TABLE-CABINET.

1,343,622.

Specification of Letters Patent. Patented June 15, 1920.

Application filed May 5, 1919. Serial No. 294,687.

To all whom it may concern:

Be it known that I, PETER KRAUSHAAR, a citizen of the United States, residing at Montebello, in the county of Los Angeles 5 and State of California, have invented new and useful Improvements in Phonograph Table-Cabinets, of which the following is a specification.

This invention relates to a phonograph cabinet, and pertains particularly to a cabinet which when closed has the appearance of a table.

The primary object of this invention is to provide a cabinet having the appearance of 15 a table and so constructed that the phonograph and its horn are housed beneath the table top. It is another object of this invention to provide a cabinet of the class described with a phonograph and horn mounted

20 ed to be drawn out and opened up in the manner of an ordinary table drawer.

In addition to the broader features of this invention, there are certain details of structure, whereby a strong, durable, and simple 25 cabinet of the form and appearance of a table may be obtained without detracting from the ornamental appearance of the table.

These objects will be more fully understood 30 as will also other objects and corresponding accomplishments of my invention from the following detailed description of an embodiment thereof. For the purpose of this description reference is had to the accompanying drawing, in which:

Figure 1 is a perspective view of a table cabinet with the phonograph closed in; Fig. 2 is a horizontal section as seen on the line 2—2 of Fig. 1; Fig. 3 is an enlarged fragmentary section taken on the line 3—3 of Fig. 2; Fig. 4 is a section taken on the broken line 4—4 of Fig. 3; and Fig. 5 is a section similar to Fig. 2 showing the phonograph in its open position and ready for 45 playing.

Referring more particularly to Fig. 1, the cabinet is shown as a table having the apron with a long side thereof divided into three panels. The opposite side of the table has 50 the same general appearance. The middle panel forms the outer wall of a sliding drawer containing the phonograph. The panel upon the opposite side forms a muffler for a telescopic horn, one section thereof

being attached to the table apron and another section communicating with the phonograph tone arm.

The table is shown as having a fixed top, beneath which is an apron having a rear portion 7 and a front portion 8. The apron is completed by end portions 9 and 10. Both the front and rear aprons are divided into three panels, the rear panels are indicated by 11, 12 and 13, see Fig. 2. The panel 12 constitutes the front wall of a sliding drawer housing the phonograph. Secured to the wall 12 at about the middle thereof and extending to the rear is a bed 14, upon which the phonograph turntable is mounted, and beneath which the motor is suspended. Extending across the bed at the rear end thereof is a wall 15 forming a rear wall for the phonograph housing.

Partition walls 16 and 17 extend transversely across the table and form side closures for the phonograph drawer. Secured thereto below the level of the bed 14 are pairs of tracks, the pair on wall 17 being indicated by 18 and 19, see Figs. 3 and 4. Extending toward the front of the table and secured to the bottom thereof are arms 20 and 21, and secured thereto are wheels riding on the rails. Referring to arm 21 brackets 22 and 23 are fixed thereto, and journaled in the brackets are wheels 24 and 25. This construction provides for easy sliding of the drawer.

The particular construction of the phonograph which is indicated generally by 26 forms no part of my invention, and the phonograph is merely shown conventionally. A tone arm 27 is suitably connected into the wall 15 and communicates with the section 28 of the telescopic horn. Section 28 is fixed to the wall 15 and slides with the drawer. It is nested within a section 29, which is fixed to the apron 8. The mouth of the horn covers the middle panel of the front apron. The panel proper consists of a sliding wall 30, which may be moved from in front of the horn opening leaving only the netting 31. The wall 30 comprises a muffler for the phonograph. Secured to the wall is a flexible metallic strip 32 connected at one end to a lever 33 pivoted at 33' and so disposed that a person at the rear of the table may reach underneath and grasp the lever to move the panel 30.

- The manipulation of the table, when the phonograph is to be played is as follows: The phonograph drawer is pulled outwardly moving the phonograph so that it is accessible. The horn section 28 moves with the drawer, the large end registering with the small end of section 29, thereby providing a complete horn. The phonograph may now be operated. Lever 33 may be manipulated to produce the proper muffling effect. If desired, the drawer may be closed without interfering with the production of the music or other phonograph sounds.
- 15 In order to shut off the noises produced by the record and needle other than that transmitted through the horn, a sliding cover is provided. This cover is like an inverted trough, comprising side walls 34 and 35. A top 36 joins the walls 34 and 35. Beads 37 and 38 are formed upon walls 16 and 17 and are disposed in grooves on walls 34 and 35. This provides a guide for the cover. The cover is open at each end so that it may be slid over the phonograph to in-

close the latter and shut off noises, when the drawer is out.

It is obvious that I have provided a phonograph cabinet having the general appearance of a table and serving all the purposes of a table. The phonograph is so disposed that when the drawer is opened up it and its horn are transverse of the table. This leaves room at the sides of the table for pigeon holes in which records may be filed.

What I claim is:

In a table having a paneled apron, the combination of a slideable drawer having a panel of said apron forming the outer wall 40 thereof, a phonograph mounted on said drawer, a section of a telescopic horn secured to said drawer, another section of said horn secured to said apron with the mouth thereof registering with a panel opposite to said first mentioned panel. 45

In witness that I claim the foregoing I have hereunto subscribed my name this 26th day of April, 1919.

PETER KRAUSHAAR.
